MARTIN T. MINOGUE, OF PHILADELPHIA, PENNSYLVANIA, ASSIGNOR, BY MESNE ASSIGNMENTS, TO SUPERIOR MOTOR SPECIALTY COMPANY, A CORPORATION OF DELAWARE.

SPARK-PLUG FOR EXPLOSIVE-ENGINES.

1,119,302.

Specification of Letters Patent.

Patented Dec. 1, 1914.

Application filed August 8, 1912. Serial No. 714,015.

To all whom it may concern:

Be it known that I, MARTIN T. MINOGUE, a citizen of the United States, residing in Philadelphia, Pennsylvania, have invented 5 certain Improvements in Spark-Plugs for Explosive-Engines, of which the following is a specification.

One object of my invention is to so construct a spark plug for explosive engines 10 as to simplify the construction of the porcelain member thereof, to permit of the ready application of the electrodes thereto and their secure retention therein, to insure good electrical contact between the electrodes and the binding posts at the outer 15 end of the plug, to provide simple and effective means for securing the porcelain member in the surrounding metallic sleeve or shell, and to permit of the use of the plug 20 either as a single spark plug or as a double spark plug.

A further object of my invention is to so construct a spark plug as to permit of the use of the same for the introduction of 25 fluid under pressure into the cylinder of the engine for starting purposes; another object is to effect the secure confinement of the plug to the cylinder and the ready release of the plug therefrom, and a final 30 object is to provide for the use of two plugs in the cylinder so as to effect a double sparking therein.

These objects I attain in the manner hereinafter set forth, reference being had to 35 the accompanying drawing, in which—

Figure 1 is a vertical section of a spark plug constructed in accordance with my invention, showing the same as designed for a double spark plug; Fig. 2 is a horizontal section, on a smaller scale, on the line $a-a$, Fig. 1; Fig. 3 is a sectional view showing the electrodes as disposed when the spark is intended for use as a single spark plug; Fig. 4 is a horizontal section on the line 45 $b-b$, Fig. 1; Fig. 5 is a horizontal section of part of the plug on the line $c-c$, Fig. 1, and Fig. 6 is a diagram illustrating the electrical connections whereby the use of two plugs in the cylinder is permitted for the 50 purpose of insuring double sparking in said cylinder.

In Fig. 1 of the drawing, 1 represents a tubular casing which carries the spark plug, this casing being screwed into the head of 55 the cylinder and being in electrical contact therewith. The bore of the casing 1

increased in diameter at its upper end for the reception of a tubular sleeve 2, a washer 4 being interposed between the top of the casing 1 and a flange which surrounds the top of the sleeve 2 (see Fig. 1). The insulating member 5 which is usually of porcelain, is, as to its lower portion, contained within the sleeve 2 and has formed in it an external groove 6 which registers with a corresponding internal groove 7 in the sleeve 2 so as to form a chamber for the reception of a split ring 8, the latter having a normal tendency to expand so as to enter the groove in the sleeve 2 without leaving the groove in the porcelain member 5, thereby firmly locking said porcelain member to the sleeve 2. In the first instance the split ring 8 is compressed into the groove 6 of the porcelain member so as to be contained wholly within the latter, and said porcelain member is then pushed down into the sleeve 2 until the grooves 6 and 7 are in register, whereupon the ring will expand into the groove 7 and lock the porcelain member and sleeve together, as indicated in Fig. 1. Escape of gas through the space between the porcelain member 5 and the sleeve 2 is prevented by a filling 3 of cement.

In preparing the porcelain member 5 for the reception of the electrodes 9, two vertical openings of a diameter large enough to receive the electrodes are formed therein, and these openings are crossed at a little distance below the tops of the same by transverse recesses 10 formed in the upper portion of the porcelain member 5 and of such depth that a bridge wall 5^a of porcelain is interposed between the two recesses so as to effectively insulate them electrically one from the other. Each of the recesses 10 receives one of the binding posts 11 of the plug, and each of these posts has, at its inner end, a head 12 with opening therethrough for the passage of the electrode 9 which is pushed up from the lower end of the plug until the upper end of said electrode passes through the head 12 and enters the upper end of the vertical opening formed in the porcelain member for its reception, lateral strain being then exerted upon the binding post 11 so as to draw its head firmly into contact with that portion of the electrode which bridges the opening 10 and thereby insure good electrical contact between the binding post and the electrode. To effect this lateral strain upon the

binding post the same is threaded throughout the greater portion of its length for the reception of a nut 14, between which and the face of the porcelain member 5 is interposed a washer 15, the threaded portion of the binding post also having another nut 16, which, in conjunction with the nut 14, serves to firmly confine the conducting wire to the binding post 11. The recesses 10 are 10 preferably of considerably greater diameter than the binding posts 11, and after the binding post has been inserted in the recess and its head engaged with the electrode 13 the recess may be filled with any suitable 15 cement prior to the application of the washer 15 and nut 14. Both the openings for the reception of the electrodes and the recesses for the reception of the binding posts are straight bored, and can thus be 20 readily formed in the porcelain member while the latter is in the plastic condition before being burned, the manufacture of the porcelain member being thereby simplified and cheapened.

25 Firmly secured to the casing 1 by means of a nut 17 and washers 18 is a ring 19 having threaded openings for the reception of clamp screws 20 which pass through openings in a pair of jaws 21, and have enlarged 30 heads 22 rounded on the under sides, and bearing upon concaved or dished washers 23 on the jaws 21, so that when the screws 20 are turned in one direction the jaws 21, which overlap the top of the sleeve 2, will 35 be pressed down upon the latter so as to confine the same firmly to the casing 1, the turning of the screws 20 in the opposite direction relieving the sleeve 2 from the pressure of the jaws 21 and permitting the 40 latter to be turned to a position out of engagement with said sleeve 2, thus permitting the latter and the porcelain member carried by it to be withdrawn from the casing 1 when it becomes necessary to 45 inspect or change the spark plugs for any reason. Each of the electrodes is curved at that end which projects below the porcelain member 5, so that by turning each electrode in the porcelain member the curved 50 lower ends of said electrodes may be caused to extend outwardly, as in Fig. 1, or inwardly as in Fig. 3, each electrode, in the former case, being independent of the other and forming the spark between its lower 55 end and the adjacent wall of the sleeve 2, while when the electrodes are adjusted as shown in Fig. 3, they coöperate with each other and form the spark between their adjoining ends. In the latter case the upper 60 end of one of the electrodes will be connected to the positive pole of the electric generator and the upper end of the other electrode will be connected to the negative pole of the same, while when the electrodes are adjusted 65 as shown in Fig. 1, so as to act independ-

ently, the upper end of each electrode may be connected to one pole of an electric generator and the opposite pole of the same may be connected to the cylinder or other ground connection, which is in electrical connection with the sleeve 2 through the casing 1.

When the double spark plug shown in Fig. 1 is used it is not intended that both of the electrodes shall be connected to the 75 electric generator at one time, only one electrode being used at a time and the other being brought into use in the event of the first being rendered inoperative at any time from any cause, and one electrode may be 80 supplied with current from one electric generator, as, for instance, a battery, while the other electrode may be supplied with current from another electric generator, as, for instance, a magneto. The current from the 85 battery will usually act as a primary for a sparking coil, the current from the secondary coil forming the spark, and the magneto will either act in the same way, or, if of sufficiently high intensity, will be connected directly to the spark plug.

It is now a common practice to start an explosive engine by introducing fluid under pressure into one or more of the cylinders instead of "cranking" the engine, as was 95 formerly customary. I employ the ring 19 as a means for effecting the fluid connection, said ring 19 having, at one side, an internally threaded nipple 24 communicating through a passage 25 with an internal 100 groove 26 in the ring, the base of the nipple being provided with a valve seat 27 for the reception of a valve 28 which prevents back flow through the nipple but does not interfere with forward flow therethrough. The 105 groove 26 communicates through one or more openings in the casing 1 with the annular space between said casing and the sleeve 2, so as to provide for the flow of fluid under pressure into the cylinder through this 110 space.

In Fig. 6 I have shown in diagrammatic form the use of my improved spark plug for the production of a double spark in the cylinder. In this figure, 30 represents the battery, 31 the magneto, 32 the spark coil, 33 and 34 the two spark plugs, and 35 a switch whereby either the battery or the magneto may be utilized as the source of electric energy, it being understood that the circuits 115 will be employed in connection with the customary commutator for properly timing the sparking of the engine. The plug 34 has its electrodes adjusted so as to act as a single spark plug, and the plug 33 has its electrodes adjusted so as to act as a double spark plug. When the circuit is closed the current enters the plug 34 at one binding post, forms a spark between the electrodes of said plug, passes thence from the other binding 120 post, passes through the coil 32, and enters the plug 33 at one binding post, forms a spark between the electrodes of said plug, passes thence from the other binding 125 post, passes through the coil 32, and enters the plug 34 at one binding post, forms a spark between the electrodes of said plug, passes thence from the other binding 130 post, and returns to the battery 30.

post and through a connection 36 to a binding post of the plug 33 and forms a spark between the corresponding electrode and the sleeve 2 of the plug, which is grounded through the cylinder. When the current is not grounded through the cylinder, both of the plugs may be similar to the plug 34, the plugs being connected as at 36 and one plug being connected to the positive pole and the other to the negative pole of the generator.

I claim:

1. In a spark plug for explosive engines, an insulating member having a longitudinal bore therethrough, an electrode extending loosely through said bore, a transverse recess crossing said bore and into which said electrode extends, a binding post projecting into said recess and having its inner end engaging the electrode, said inner end being of less diameter than said transverse recess, and means for imparting endwise movement to said binding post to cause it to bind upon the electrode and bend the same at a point in said recess and thus make a good electrical contact as well as lock the electrode against removal.

2. In a spark plug, the combination of an insulating body having a longitudinal bore, said bore having a transverse recess crossing it, a bendable electrode extending loosely through said bore and entering said recess, a binding post extending into said recess and engaging said electrode, the part that engages the electrode being less in diameter than said transverse recess, the binding post having a threaded stem and a pair of nuts on the latter, one for imparting endwise

movement to the binding post to bend the electrode at a point in said recess and the other for confining the conducting wire to the binding post, an abutment being provided for the former nut.

3. In a spark plug for explosive engines, an insulating member having a straight bore therein for the reception of an electrode, a transverse recess communicating with said bore and extending inwardly beyond the same, a perforated binding post contained in said recess, an electrode contained in said bore and projecting into the perforation of the binding post, and means for imparting outward draft to said binding post so as to cause it to bear against said electrode.

4. In a spark plug for explosive engines, an insulating member having therein a straight bore and a transverse recess, the bore crossing the recess so as to present a portion on each side thereof, and the recess extending inwardly beyond the bore, a perforated binding post contained in said recess, an electrode contained in said bore and extending across the recess and through the perforation of the binding post, and means for imparting outward draft to said binding post so as to cause it to bear against the electrode.

In testimony whereof, I have signed my name to this specification, in the presence of two subscribing witnesses.

MARTIN T. MINOGUE.
